DESIGN FOR A RUG.

Design No. 14,377, dated October 30, 1883.

R. PAUL HEMMING,
J. GORDON SHOWAKER,
WILLIAM JARDEN.

UNITED STATES PATENT OFFICE.

R. PAUL HEMMING, OF PHILADELPHIA, PA., ASSIGNOR TO JOHN H. BROMLEY, JOSEPH H. BROMLEY, AND EDWARD BROMLEY, ALL OF SAME PLACE.

DESIGN FOR A RUG.

SPECIFICATION forming part of Design No. 14,377, dated October 30, 1883.
Application filed August 25, 1883. Term of patent 3½ years.

To all whom it may concern:

Be it known that I, R. PAUL HEMMING, a citizen of the United States, and a resident of Philadelphia, Pennsylvania, have invented and produced a Design for Rugs, &c., of which the following is a specification.

The nature of my invention is fully set forth in the accompanying photographic illustration, to which reference is made.

What I claim as new is—

The design for rugs, as shown.

Witnesses: R. PAUL HEMMING,

J. GORDON SHOWAKER,

WILLIAM JARDEN.
